UNITED STATES PATENT OFFICE.

JAMES W. COPES, OF PHILADELPHIA, PENNSYLVANIA.

BOILER-FEED REGULATOR.

SPECIFICATION forming part of Letters Patent No. 662,687, dated November 27, 1900.

Application filed September 9, 1899. Serial No. 730,036. (No model.)

To all whom it may concern:

Be it known that I, JAMES W. COPES, of Philadelphia, in the State of Pennsylvania, have invented certain new and useful Improvements in Boiler-Feed Regulators, whereof the following is a specification, reference being had to the accompanying drawings.

My invention relates to that class of devices wherein an expansible tube is connected with a boiler above and below the water-line of the latter, so that the difference in temperature between the contained steam and water may be utilized in the expansion and contraction of said tube.

It is the object of my invention to provide simple and efficient means for automatically regulating the flow of water to a boiler provided with an expansible tube, as aforesaid; and to this end my invention comprises devices in coöperative relation with said tube whereby the operation of the boiler-feed pump may be adjustably predetermined with precision.

In the accompanying drawings, Figure 1 is a front elevation of a boiler, showing a convenient embodiment of my invention applied thereto. Fig. 2 is a vertical sectional view of the steam-throttle valve of the boiler-feed pump and the automatically-operated governor of said valve. Figs. 3 and 4 are respectively a plan view and side elevation of the joint between the expansible tube and the valve-operating lever connected therewith.

In said figures, A is a boiler provided with the feed-water pump B. The normal water-line of said boiler is indicated at a, and the expansible tube C is connected with the boiler at c below said water-line and at c' above said water-line, so as to contain water in its lower portion and steam in its upper portion in proportions determined by the level of the water in the boiler. The extremity C' of said tube is fixed in the standard A² upon said boiler, but the opposite free extremity C² is pivotally connected with the bell-crank lever D below the fulcrum d, as shown in detail in Figs 3 and 4. Said lever is mounted to oscillate in the flexible standard A³, fixed at its foot upon the boiler. The rod E is fixed at one end in the standard A², and its opposite end extends through the cylindrical bearing

block e, which is mounted for oscillation in a recess in the side of the standard A³. Said rod E is threaded and provided with a nut e' beyond the bearing e, and said standard A³ is sufficiently flexible to permit of the micrometer adjustment of the relation of the parts by shifting said nut longitudinally with respect to said rod, the shape of the block e permitting the change in the angular relation of the parts. Said lever D is connected by the link d' with the arm f' of the toggle-lever, whose other arm f' is pivotally connected by the member f² with the cross-head f³, to which is fixed the stem f⁴ of the check-valve F. Said valve serves to control the flow of the feed-water in the pipe G from the pump B to the boiler A.

The lever-arm f' is provided with the weight F', which is adjustably fixed thereon to balance or partially balance the pressure within the pipe G, and thus relieve the expansible tube C from unnecessary strain.

The arrangement of the parts just described is such that they normally occupy the position shown in Fig. 1, wherein said valve F is closed. However, it is to be understood that upon the fall of the water within the boiler to a point below the normal line a the increased extent of the tube C exposed to the temperature of the steam causes said tube to expand and uplift the lever D, link d', and lever-arm f', thereby thrusting the lever-arm f' and link f² out of alinement, raising the cross-head f³ and stem f⁴ of the valve F and opening the latter.

B' is the steam-supply pipe leading from the main steam-pipe A' of the boiler A to the pump B, and B² is the exhaust-pipe leading from said pump. In said supply-pipe B' is a throttle-valve H, the stem h of which is coupled with the stem i of the governor-piston I, arranged to reciprocate within the governor-cylinder I'. Above said piston the cylinder I' is connected by the pipe g with the feed-water pipe G, and below said piston said cylinder is connected by the pipe b' with the steam-supply pipe B'.

The frame H' connects the casing of the valve H with the governor-cylinder I'. The lever H², which is pivotally connected with the coupling-piece h', is mounted to oscillate upon the fulcrum h in said frame and is pro-

vided with a weight H^3 , which may be adjustably fixed thereon. Said weight is so adjusted as to overbalance the weight of the moving parts of said valve and governor and 5 serves to open said valve H whenever the piston I is relieved from the excess of pressure above it in the cylinder I' . However, under normal conditions the water-pressure in said cylinder I' above said piston I is such as to 10 maintain the parts in the position shown in Fig. 2, with the ports h^x of the valve H closed by the valve-plunger H^x , thus preventing passage of the steam through the pipe B' to the steam-chest of the pump B .

15 The operation of the device is as follows: The temperature of the steam in the upper portion of the expansible tube C is higher than that of the water in the lower portion of said tube, and therefore when the water 20 falls in the boiler below the normal level a to which the parts have been calibrated, as aforesaid, the increased area of the tube C exposed to the temperature of the steam causes said tube to further expand and 25 uplift the lever D and by means of the link d' to uplift the lever-arm f' and shift the lever-arm f' and link f^2 , thus raising the cross-head f^3 and stem f^4 of the valve F and opening the latter. The pipes G and g below the 30 valve F being thus placed in communication with the boiler, the water-pressure in the governor-cylinder I' above the piston I is equalized by the steam-pressure from the pipe b' below said piston-head, permitting the weight 35 H^3 to shift the plunger H^x , thus opening the steam-ports h^x and permitting the steam to flow through the pipe B' to actuate the pump B . The pump B , being brought into operation, as above described, continues to take wa- 40 ter through the pipe G' and deliver it through the pipe G to the boiler A until the water reaches the normal level a therein, whereupon the area of the tube C exposed to the action of the steam being reduced to the normal limit said tube contracts to its normal 45 length and closes the valve F . After the closure of the valve F the pump B continues to operate until the water-pressure in the pipes G and g and in the upper portion of the 50 governor-cylinder I' is such as to lower the piston I and valve-plunger H^x against the steam-pressure in the lower portion of said cylinder I' , supplemented by the weight H^3 , thus closing the ports h^x of the throttle-valve 55 H and stopping the pump.

I am aware that it is not broadly new to provide an expansible tube for the purpose described. I believe it to be new, however, to so arrange such a tube as to permit of the 60 micrometer adjustment of the parts connected therewith and to effect the control of the steam-supply of a boiler-feed pump by the co-operation of intermediate devices, such as herein described. I therefore do not desire 65 to limit myself to the precise construction and arrangement of the parts which I have illustrated, as it is obvious that various modifica-

tions may be made therein without departing from the spirit of my invention.

I claim—

1. In a boiler-feed regulator, the combination with an expansible tube, connected with the boiler above and below the normal water-level therein, of a fixed support for one end of said tube, a lever connected with the free end of said tube, a valve in operative relation with said lever, an adjustable support for the fulcrum of said lever, and means to adjustably shift the fulcrum of said lever by flexure of said support, substantially as set forth. 70 75 80

2. In a boiler-feed regulator, the combination with an expansible tube, connected with the boiler above and below the normal water-level therein, of a feed-water pipe for said boiler, a valve in said water-pipe, toggle-levers arranged to operate said valve, and means operatively connecting said expansible tube and said toggle-levers, substantially as set forth. 85

3. In a boiler-feed regulator, the combination with an expansible tube connected with the boiler above and below the normal water-level therein, of a feed-water pipe for said boiler, a valve in said water-pipe, a reciprocatory cross-head, fixed to the stem of said valve, toggle-levers arranged to reciprocate said cross-head, and means operatively connecting said expansible tube, and said toggle-levers, substantially as set forth. 90 95

4. In a boiler-feed regulator, the combination with an expansible tube, connected with the boiler above and below the normal water-level therein, of a fixed support A^2 , for one extremity of said tube, a pivotal connection for the opposite extremity of said tube, a valve in operative relation with said pivotal connection, a fixed tension-rod E , a flexible standard A^3 , a bearing e , in said standard through which said rod E is entered, and a nut e' , on said rod arranged to adjustably determine 100 the relation of said standard A^3 , and the pivoted extremity of said tube, substantially as set forth. 105 110

5. In a boiler-feed regulator, the combination with an expansible tube, connected with the boiler above and below the normal water-level therein, of a feed-water pipe for said boiler, a valve in said water-pipe, a toggle-lever connected at one extremity with the stem of said valve, a weight, adjustable upon 115 the other extremity of said toggle-lever, and means operatively connecting said expansible tube and said toggle-lever, substantially as set forth. 120

6. In a boiler-feed regulator, the combination with an expansible tube, connected with the boiler above and below the normal water-level therein, of a feed-water pump, a feed-water pipe from said pump to said boiler, a valve in said water-pipe, a steam-pipe from 125 said boiler to said pump, a valve in said steam-pipe, and hydraulic means connecting the valve in said water-pipe with the valve in said steam-pipe, in such relation 130

with said expansible tube as to predetermine the coöperative actuation of said two valves by said expansible tube, substantially as set forth.

- 5 7. In a boiler-feed regulator, the combination with an expansible tube, connected with the boiler above and below the normal water-level therein, of a feed-water pump, a feed-water pipe from said pump, to said boiler, a valve in said water-pipe, a steam-pipe from said boiler to said pump, a valve in said steam-pipe, comprising a reciprocatory plunger, a piston operatively connected in axial alinement with said plunger, a cylinder

containing said piston intermediate of its length, a pipe connection between one end of said cylinder and said water-pipe, a pipe connection between the other end of said cylinder and said steam-supply pipe, and means operatively connecting said expansible tube 15 with the valve in said water-pipe; arranged to operate said two valves in predetermined relation, substantially as set forth.
